(No Model.)

W. TOEPFER.

DEVICE FOR OPERATING THE BOTTOM DOORS OF STEEP TANKS, &c.

No. 390,533.

Patented Oct. 2, 1888.

Fig. 1.

UNITED STATES PATENT OFFICE.

WENZEL TOEPFER, OF MILWAUKEE, WISCONSIN.

DEVICE FOR OPERATING THE BOTTOM DOORS OF STEEP-TANKS, &c.

SPECIFICATION forming part of Letters Patent No. 390,533, dated October 2, 1888.

Application filed June 8, 1888. Serial No. 276,451. (No model.)

To all whom it may concern:

Be it known that I, WENZEL TOEPFER, a citizen of the United States, residing at Milwaukee, in the county of Milwaukee, and in the State of Wisconsin, have invented certain new and useful Improvements in Devices for Operating the Bottom Doors of Steep-Tanks, &c.; and I do hereby declare that the following is a full, clear, and exact description thereof.

10 My invention relates to devices for operating the bottom doors of steep-tanks, &c., and will be fully described hereinafter.

In the drawings, Figure 1 is a section of a tank with the door closed by my device. Fig. 15 2 is a like section with the door partly closed and locked in this position. Fig. 3 shows the door entirely open, and Fig. 4 is a section.

A is the tank, to which, on its under side, are secured two bars, B, having ears *a* on one end, 20 to which the door C is hinged, and on their front ends, which project downward at right angles, is secured a strong plate, *b*, in which is a slot, *b'*. A curved arm, D, projects from the bottom of door C, and to this is pivoted one 25 end of an operating-bar, E, the other end of which is formed with a handle, F, that is preferably slightly downturned, and a short distance from its outer end bar, E, is formed with two shoulders, *c* and *d*. The shoulder *c* is cam-30 shaped and rather more abrupt in front than in its rear, while the shoulder *d* is formed by notching the bar from the front.

G is a cam-lever having a projection, *f*, for engagement with the shoulder *c* of operating-bar E, and having another shoulder, *g*, which is notched at *h* and *i*. A latch, *j*, is fitted in ways *k*, that are secured to the face of plate *b*, and this latch is designed for engagement with notches *h*, as shown in Fig. 1, and *i*, as in Fig. 2.

40 The door C is formed with a grooved flange, *m*, in which is fitted a packing-ring, *m'*, that rests when the door is closed up against the edge of the flange A' of the opening in the bottom of the tank.

45 In operation when the door is open the parts

are in the position shown in Fig. 3. Now to partly close the door, as in Fig. 2, the bar E is pushed in until the notch *d* catches on plate *b*. When the door is to be entirely closed, a handle, *G'*, is placed on the cam-lever and latch *j* 50 is lifted, after which the operator depresses the handle *G'*, causing the projection *f* of lever G to engage projection *d* on bar E and force the bar in to shut the door, after which the latch *j* is forced into notch *i* and the door is 55 securely closed. The handle *G'* may now be removed and taken away. When the door is to be opened, the handle is again applied, latch *j* lifted as well as the handle *G'*, and the bar moves out until the notch *c* catches on the plate 60 *b*, and the latch is then dropped into notch *h*.

Having thus fully described my invention, what I claim as new, and desire to secure by Letters Patent, is—

1. The combination, with the swinging door 65 of a tank, of an operating-bar pivoted thereto at one end, bars projecting from under the tank, a holding-plate carried thereby, a cam-lever adapted to engage the operating-bar, and a locking-latch for said cam-lever, substantially as described.

2. The combination, with the door and its operating-bar, the latter shouldered, as described, of a holding-plate suspended from the bottom of the tank and the operating cam-lever 75 pivoted to said holding-plate over the path of the operating-bar, substantially as described.

3. The combination, with the door and its operating-bar, of the holding-plate suspended from the bottom of the tank, cam-lever, and a 80 latch for engaging notches in the cam-lever for locking it when adjusted.

In testimony that I claim the foregoing I have hereunto set my hand, at Milwaukee, in the county of Milwaukee and State of Wisconsin, 85 in the presence of two witnesses.

WENZEL TOEPFER.

Witnesses:

S. S. STOUT,
N. E. OLIPHANT.
